EMBLEM DEVICE

George W. Emmert, Winnetka, Ill., assignor to Federal Premium Service, Inc., Evanston, Ill., a corporation of Illinois

Application August 1, 1956, Serial No. 601,533

9 Claims. (Cl. 40—1.5)

The present invention relates to emblem devices and more particularly to an improved emblem structure that is ideally suited for use, for example, for so called lapel pins or lapel emblems of the type distributed from time to time in great numbers by institutions and organizations of various kinds.

One of the major costs heretofore involved in the manufacture of small lapel type emblems and the like has been the expense of providing, in conjunction with the emblems, some means by which they may be readily attached to the clothing of the wearer. Organizations, for example, such as the Red Cross, Community Chest, and others who sponsor fund raising campaigns, have constantly sought ways and means to reduce the expense of the organizational emblems that they distribute in great numbers to their contributors and to their workers. By resorting to the use of plastic rather than metal for the bodies of their emblems, some progress has been made by organizations of this type in reducing the total cost of their emblems, but even with plastic emblems the relative cost of the manufacturing step of applying to the plastic bodies the means for securing the emblems to the clothing has remained very high and has heretofore been thought by those skilled in the art to be an item of cost that could not be overcome or avoided. Though the cost of applying the securing means to a single emblem may heretofore have been only a fraction of a cent, it will readily be appreciated that this cost has been a very substantial factor in the total cost of manufacture when the production of hundreds of thousands, or millions, of the emblems has been involved.

One of the principal objects of the present invention is to provide an emblem device adapted to be attached to clothing or to other articles, wherein the cost of the structural means for attaching the emblem to the clothing is reduced to a minimum and the heretofore relatively costly manufacturing step of securing the attaching means to the emblem is entirely avoided, thereby providing a less expensive emblem device than any heretofore known to me. Another object of the invention is to provide an emblem device of the character just stated that may be attached to the clothing by a simple, ordinary, straight house pin which is secured to the emblem device, not by the manufacturer, but by the user himself at the time he applies the emblem to the clothing. Still another object of the invention is to provide an emblem device of the aforesaid kind that is of single piece construction and may be easily and inexpensively molded of elastomeric thermoplastic material, such as polyethylene, but yet is provided on its backside with means for guiding the direction of movement of the attaching pin when the emblem is applied by the user to his clothing, and is also provided with means by which the emblem device is secured to the pin.

These and other objects and advantages of the present invention will be apparent from the following description of a preferred embodiment thereof, and a modification

2

of that embodiment, taken with the accompanying drawing, wherein:

Fig. 1 is an elevational view of an emblem device in accordance with the present invention, showing the emblem as it may appear when applied to an article of clothing;

Fig. 2 is a longitudinal cross-sectional view taken through the emblem and through the fabric of the article of clothing substantially along the line 2—2 in Fig. 1, showing in broken lines the position of the emblem securing pin immediately before attachment of the emblem to the article of clothing is made;

Fig. 3 is an elevational view of the back side of the emblem shown in Figs. 1 and 2, showing the securing pin in the position that it occupies after the emblem has been attached to the clothing;

Fig. 4 is a cross-sectional view taken substantially along the line 4—4 in Fig. 3;

Fig. 5 is a similar view taken substantially along the line 5—5 in Fig. 3;

Fig. 6 is a cross-sectional view similar to Fig. 4, but showing the appearance of the H-shaped embossment on the back side of the emblem, together with a diaphragm provided between the legs of the embossment, before the diaphragm is pierced by the pin during the mounting of the emblem upon the clothing;

Fig. 7 is a modification of the emblem structure shown in the preceding views; and

Fig. 8 is a cross-sectional view taken substantially along the line 8—8 in Fig. 7, showing the manner in which the modified emblem is attached to an article of clothing or other fabric.

In the drawing the numeral 10 designates, generally, the body portion of an emblem constructed in accordance with the present invention. This body portion of the emblem may have any desired outline or edge configuration, and its face 11 may likewise carry any design or information desired. In the present instance, for purposes of simplicity, the emblem body has been shaped to resemble a feather, but it will be appreciated that the emblem body may resemble the symbol commonly employed by the Red Cross or that used by any other organization or group.

As will be more fully explained hereinafter, the present emblem is preferably formed or molded as a single piece from any suitable elastomeric material having rubber-like qualities. An example of one such suitable material is the synthetic, organic, elastomeric, thermoplastic material known as polyethylene.

The back side 12 of the body 10 of the emblem is preferably flat or planar and has an H-shaped embossment 13 integrally formed thereon. This H-shaped embossment is comprised of a pair of substantially parallel spaced apart legs 14 and 15, the adjacent walls of which define a longitudinally extending guide passage adapted to receive a straight pin 16 which may be of the common ordinary household variety. The guide passage provided by the adjacent walls of the two legs 14 and 15 of the H-shaped embossment is laterally traversed by the cross-bar 17 of the H which is formed integrally with the rear surface 12 of the body of the emblem and also with the legs 14 and 15 of the H-shaped embossment. This cross-bar 17 of the H has a thickness such that, due to the elastic rubber-like quality of the material from which the emblem device is formed, it provides an elastic, resilient diaphragm extending across the guide passage.

The H-shaped embossment 13 is preferably located toward one end of the body 10 of the emblem, and a second embossment 18 is integrally formed upon the rear side 12 of the emblem in alignment with the previously mentioned guide passage for the pin 16. The

second embossment 18 is provided with a face 19 directed toward the H-shaped embossment 13 and this face 19 is preferably shaped so as to provide a V-shaped recess on the second boss, as best illustrated in Fig. 3.

In applying the emblem to an article of clothing or to any other fabric, the fabric 20 is gripped by the fingers so as to provide a shallow fold 21, whereupon the emblem is placed over the fold so that the fold lies between the H-shaped embossment 13 and the second embossment 18, as indicated in Fig. 2. The pin 16 is then placed in the position shown by the broken lines in Fig. 2 with the point of the pin disposed in the guide passage between the adjacent upper ends of the legs 14 and 15 of the H-shaped embossment. The pin 16 is then moved downwardly so that its point pierces the diaphragm provided by the cross-bar 17 of the H-shaped embossment. After piercing the diaphragm, the pin penetrates the fold 21 of the fabric and emerges therefrom, whereupon the point of the pin comes into contact with the face 19 of the embossment 18 and penetrates and is buried in that face. This simple longitudinal movement of the pin is guided by the adjacent walls of the guide passage provided by the legs 14 and 15 of the H-shaped embossment, and the pin thus tends to be guided in the proper direction to cause its point to engage and penetrate the face 19 of the boss 18. The V-shape of the face 19 tends to direct the point of the pin to the central portion of the boss 18 so that the pin point will be embedded properly in that boss.

From the foregoing description it will be observed that the attachment of the present emblem to the fabric 20 may be very easily accomplished, and when the pin 16 has been inserted in the manner just described, the projection of the pin through the diaphragm-like cross-bar 17 of the embossment 13, and the embedding of the pin point in the boss 18, not only secures the emblem to the pin 16, but also secures both the pin and the emblem to the fabric article. In this connection it will be noted that the piercing movement of the pin 16 through the resilient, elastic diaphragm-like cross-bar 17 of the H-shaped embossment 13 creates a state of compression in the material of the diaphragm about the body of the pin, causing this material to grip the pin and thus tend to prevent withdrawal thereof. It will also be noted that that portion of the diaphragm immediately surrounding the body of the pin is depressed slightly at 17a into the shape of a funnel as the pin engages and pierces the diaphragm. Thus, any effort to withdraw the pin will tend to pull the material of this funnel-shaped portion 17a of the diaphragm upwardly, thereby tending still further to increase the state of compression of the material about the pin and therefore increase the resistance to the removal of the pin. This effectively retains the pin in the position shown in Fig. 2, and prevents inadvertent removal of the emblem from the fabric article.

The modified form of the emblem illustrated in Figs. 7 and 8 differs from the form shown in the other figures of the drawing only in that the second boss 18 is eliminated therefrom. This elimination of the boss 18 has been found to be permissive in cases where the emblem, while mounted upon the fabric article, is not likely to be brushed heavily in such a way as to tend to raise the emblem and the pin 16 with respect to the fabric. If desired, when the emblem is manufactured without the boss 18, as shown in Figs. 7 and 8, the cross-bar 17 of the H-shaped embossment, and thus the diaphragm provided thereby, may have a somewhat greater thickness than that necessary when the boss 18 is employed. This increased thickness in the diaphragm-like cross-bar 17 of the H-shaped boss tends to give the diaphragm increased rigidity which prevents the

lower end of the body of the emblem from being drawn outwardly with respect to the fabric article and the pin 16.

It will readily be appreciated from the above description and from the drawing that emblem devices may be manufactured in great numbers in accordance with the present invention very inexpensively. This advantage flows from the fact that the emblem device may easily be molded as an integral unit from inexpensive thermoplastic materials and without the necessity of applying the fastening pin to the emblem device during its manufacture. The fastening pin in the present case is secured to the emblem device by the user himself at the same time the device is applied to the fabric article, thereby completely eliminating the heretofore unavoidably expensive manufacturing step of securing the fastening pin to the emblem body.

If desired, distribution of the present emblem may be made by placing each of the emblems, along with the straight pin 16, in a cellophane bag. This method of distribution not only insures that the recipient of the emblem will receive the emblem device along with the attaching pin, but it also provides the distributor with an excellent medium upon which he may print instructions for applying the emblem to the clothing and also any such information as he may desire to give with regard to the significance of the emblem.

The foregoing description has been given for clearness of understanding only and no unnecessary limitations should be inferred therefrom, for it will be appreciated by those skilled in the art that numerous variations may be made in the emblem device illustrated, without departing from the spirit and scope of the appended claims.

I claim:

1. A single piece emblem device for attachment to a fabric article by means of a pin, comprising an emblem body having integrally formed on the backside thereof a pair of rearwardly projecting, substantially parallel, spaced apart walls defining a pin receiving guide passage therebetween, an elastic diaphragm integral with said body and with said walls and extending transversely across said guide passage in position to be pierced by a pin when the same is inserted longitudinally through said guide passage and into the fabric article, said guide passage serving to guide said pin during said longitudinal movement thereof and said diaphragm gripping the pin when pierced thereby to retain the pin in said guide passage, said diaphragm thereby serving to retain said emblem body upon the pin and thus upon the fabric article.

2. A single piece emblem device for attachment to a fabric article by means of a pin, comprising an emblem body having integrally formed on the backside thereof a pair of rearwardly projecting, substantially parallel, spaced apart walls defining a pin receiving guide passage therebetween, an elastic diaphragm integral with said body and with said walls and extending transversely across said guide passage in position to be pierced by the pin when the same is inserted longitudinally through said guide passage and into the fabric article, said guide passage guiding the pin during said longitudinal movement thereof, and a rearwardly projecting boss integrally formed on said backside of said body with a face thereon in alignment with said guide passage to be penetrated by the pointed end of the pin after the end has been passed through said diaphragm and through a portion of the fabric article, said diaphragm gripping the pin to retain the same in said guide passage, and said diaphragm and said boss cooperating to retain said emblem body upon the pin and thus upon the fabric article.

3. The combination set forth in claim 2, wherein said face on said boss has a recess therein for guiding the

pointed end of the pin to a central portion of said face before the pointed end penetrates said face.

4. An emblem device for attachment to a fabric article by means of a straight pin, comprising an emblem body having a pair of rearwardly projecting, substantially parallel, spaced apart walls on the backside thereof defining a pin receiving guide passage therebetween, a resilient diaphragm extending transversely across said guide passage in position to be pierced by the straight pin when the same is inserted longitudinally through said guide passage and into the fabric article, said resilient diaphragm gripping the pin when pierced thereby to retain the pin in said guide passage, said diaphragm thereby serving to retain said emblem body upon the pin and thus upon the fabric article.

5. An emblem device for attachment to a fabric article by means of a straight pin, comprising an emblem body having a pair of rearwardly projecting, substantially parallel, spaced apart walls on the backside thereof defining a pin receiving guide passage therebetween, a resilient diaphragm extending transversely across said guide passage in position to be pierced by the straight pin when the same is inserted longitudinally through said guide passage and into the fabric article, said guide passage guiding the pin during said longitudinal movement thereof, and a rearwardly projecting boss of relatively soft material on said backside of said emblem body with a face thereon in alignment with said guide passage to be penetrated by the pointed end of the pin after the pointed end has been passed through said diaphragm and through a portion of the fabric article, said diaphragm gripping the pin to retain the same in said guide passage, and said diaphragm and said boss cooperating to retain said emblem body upon the pin and thus upon the fabric article.

6. A single piece emblem device formed entirely of resilient thermoplastic elastic material and constructed for attachment to a fabric article by means of an ordinary straight house pin, comprising an emblem body having an H-shaped embossment formed on the backside thereof and projecting rearwardly from said body a distance greater than the diameter of the body of the pin, the lateral legs of said H-shaped embossment defining a pin receiving guide passage therebetween and the cross-bar of said H-shaped embossment providing a resilient diaphragm extending transversely across said guide passage in position to be pierced by the pin when the same is inserted longitudinally through said guide passage and into the fabric article, said guide passage guiding the pin during said longitudinal movement thereof and said diaphragm gripping the pin when pierced thereby to retain the pin in said guide passage, said diaphragm thereby serving to retain said emblem body upon the pin and thus upon the fabric article.

7. A single piece emblem device formed entirely of resilient thermoplastic elastic material and constructed for attachment to a fabric article by means of an ordinary straight house pin, comprising an emblem body having an H-shaped embossment formed on the backside thereof and projecting rearwardly from said body a distance greater than the diameter of the body of the pin, the lateral legs of said H-shaped embossment defining a pin

receiving guide passage therebetween and the cross-bar of said H-shaped embossment providing a resilient diaphragm extending transversely across said guide passage in position to be pierced by said pin when the same is inserted longitudinally through said guide passage and into said fabric article, said guide passage guiding the pin during said longitudinal movement thereof, and another rearwardly projecting embossment formed on said backside of said emblem body with a face thereon in alignment with said guide passage to be penetrated by the pointed end of the pin after the pointed end has been passed through said diaphragm and through a portion of the fabric article, said resilient diaphragm gripping the pin to retain the same in said guide passage, and said diaphragm and said second embossment serving to retain said emblem body on the pin and thus on the fabric article.

8. A single piece emblem device for attachment to a fabric article by means of a pin comprising an emblem body having integrally formed on the backside thereof a pin receiving guide passage, an elastic diaphragm integral with said body and with said guide passage and extending transversely across said guide passage in position to be pierced by a pin when the same is inserted longitudinally through said guide passage and into the fabric article, said guide passage serving to guide said pin during said longitudinal movement thereof and said diaphragm gripping the pin when pierced thereby to retain the pin in said guide passage, said diaphragm thereby serving to retain said emblem body upon the pin and thus upon the fabric article.

9. A single piece emblem device for attachment to a fabric article by means of a pin comprising an emblem body having integrally formed on the backside thereof a pin receiving guide passage, an elastic diaphragm integral with said body and with said guide passage and extending transversely across said guide passage in position to be pierced by a pin when the same is inserted longitudinally through said guide passage and into the fabric article, said guide passage serving to guide said pin during said longitudinal movement thereof, and a rearwardly projecting boss integrally formed on said backside of said body with a face thereon in alignment with said guide passage to be penetrated by the pointed end of the pin after the end has been passed through said diaphragm and through a portion of the fabric article, said diaphragm gripping the pin to retain the same in said guide passage, said diaphragm and said boss cooperating to retain said emblem body upon the pin and thus upon the fabric article.
